WORK FEEDING MECHANISM FOR SEWING MACHINES

Rudolph Becker, North Plainfield, N. J., assignor to The Singer Manufacturing Company, Elizabeth, N. J., a corporation of New Jersey

Application May 22, 1945, Serial No. 595,099

15 Claims. (Cl. 112—215)

1

This invention relates to sewing machines, and more particularly to work-feeding mechanisms for sewing machines of the heavy duty, multiple needle type.

The invention has as a primary object to provide an unusually strong work-feeding mechanism, for heavy duty sewing machines, which is positive in its action and rigid in construction so that it will not be distorted under the heavy stresses to which it is subjected during operation of the machine.

Another object of the invention is to provide a heavy duty feeding mechanism for sewing machines in which both the power to lift the work-feeding element and the power to give it its work-advancing movement are each applied at a plurality of spaced points, thereby avoiding distortion of the parts when under heavy stresses.

A further object of the invention is to provide, in a dual actuated work-feeding mechanism, means for simultaneously and equally adjusting both of the feed actuating means.

Still another object of the invention is to provide, in a sewing machine work-feeding mechanism, improved means for leveling or tilting the feed-dog as may be desired.

With the above and other objects in view, as will hereinafter appear, the invention comprises the devices, combinations and arrangements of parts hereinafter set forth and illustrated in the accompanying drawings of a preferred embodiment of the invention, from which the several features of the invention and the advantages attained thereby will be readily understood by those skilled in the art.

In the drawings,

Fig. 1 is a front elevation of a heavy duty sewing machine embodying the present invention.

Fig. 2 is a horizontal sectional view taken substantially on the line 2—2 of Fig. 1, with the various cover-plates omitted.

Fig. 3 is a transverse vertical sectional view taken substantially on the line 3—3 of Fig. 2.

Fig. 4 is a transverse sectional view taken substantially on the line 4—4 of Fig. 2.

Fig. 5 is a view similar to Fig. 3, but with certain parts omitted and showing, in full and dotted lines, parts of the feeding mechanism in two positions of adjustment.

Referring more specifically to the drawings, the invention is disclosed as embodied in a sewing machine having a frame comprising a pan-like bed or base 1, a standard 2 and an overhanging bracket-arm 3 terminating in a bracket-arm head 4. Journaled in bearings 5, lengthwise of the

2

bracket-arm, is a main or arm shaft 6 carrying, at its rear end, a combined belt and hand wheel 7 through which the shaft 6 is driven from any suitable source of power.

5 Mounted in the head 4, for endwise reciprocation, are two needle-bars 8, each having fixedly secured to its lower end, a needle carrying block 9. Secured in and extending through the blocks 9 are two horizontally disposed rods 10 upon which are adjustably secured a plurality of needle-carrying blocks 11 each similar to the blocks 9. Each of the blocks 9 and 11 is adapted to carry a needle N, only three of which are shown. Any suitable number of blocks 11 may be mounted 10 upon the rods 10 and, by adjusting them along the rods and securing them thereto, any desired spacing of the needles and consequently any desired spacing of the seams formed thereby may be obtained.

20 Cooperating with each of the needles, in the formation of stitches, is a chain stitch looper L, also of which only three are shown. These loopers may be of the thread-carrying variety or the non-thread-carrying variety dependent upon 25 whether a two thread or single thread chain-stitch seam is desired. The loopers L are secured in a looper-carrier 12 in proper position to cooperate with its complementary needle. The looper-carrier, and the loopers carried thereby, 30 are given oscillatory and orbital movements from a rotary feed- and looper-actuating shaft 13, journaled in bearings 14 in the base, through mechanism designated generally as x. Inasmuch as the looper actuating mechanism forms no part 35 of the present invention, detailed illustration and description thereof is deemed unnecessary.

The shaft 13 is rotated from the main shaft 6 through the medium of a one-to-one pulley and clip-belt drive, located in a vertically disposed 40 cavity 2^a in the standard 2, and comprising a grooved pulley 6^a on the shaft 6, a similar pulley 13^a on the shaft 13 and a clip-belt 6^b connecting those pulleys.

45 The needle-bars 8, and the needles carried thereby, are given endwise reciprocations from the arm shaft 6 through mechanism designated generally as y, and in timed relation with the movements of the loopers.

50 Secured upon the upper side of the bed 1 are suitable cover-plates 1^a and a work-supporting throat-plate 1^b having therein slots 15 through which operate the sections of a feed-dog 16 of a lower four-motioned work-feeding mechanism hereinafter to be described. During the time that 55 the feed-dog is below the upper face of the

throat-plate, the work is held on the throat-plate by two presser-feet 17 each secured upon the lower end of a spring-depressed presser-bar 17^a mounted in the head 4. When the feed-dogs are above the upper surface of the throat-plate, during a work-feeding movement, the presser-feet yieldingly bear upon the work and therefore cooperate with the feed-dog in the feeding of the work.

The overall spacing of the outside needles is 10 relatively great and, as the presser-feet and feed-dog must be greater in width than the overall spacing of the needles, it follows that the presser-feet and feed-dog also are of considerable width. This, together with the fact that the machine is 15 designed for use on heavy materials, necessitates that a relatively heavy spring pressure be applied to the presser-feet to insure proper feeding of the work. During the feeding stroke this pressure is transmitted directly to the feed-dog and 20 thereby to the feed-bar or frame which carries the feed-dog.

The present improved work-feeding mechanism includes the feed-dog 16 and a horizontally disposed substantially U-shaped feed-frame 18 comprising two slide-bars 19, to the forward ends of which the feed-dog 16 is secured, and a cross-bar 20 to which the rear ends of the slide-bars 19 are connected. The feed-frame 18 is slidably mounted on two horizontally disposed guide-bars 21 pivotally connected, at 22, to the bed of the machine. The feed-frame is reciprocated on its 25 guide-bars by two independent drives comprising two aligned rock-shafts 23 and 24 journaled, respectively, in bearings 25 and 26, 26' in the machine-base.

The rock-shaft 24 is oscillated from a feed-drive eccentric 31 on the rotary feed and looper actuating shaft 13 through the medium of a pitman 32 having one end surrounding the eccentric 31 and its other end connected, at 29, to the upper end of a rock-arm 33 fixed to the shaft 24. (See Figs. 2 and 4.) The rock-shaft 23 is similarly oscillated from an eccentric 27 on the shaft 13 through a pitman 28 connecting the eccentric with the upper end of a rock-arm 30 secured upon the shaft 23.

The eccentrics 27, 31, pitmans 28, 32 and the rock-arms 30, 33 are identical and therefore the rock-shafts 23, 24 are oscillated synchronously from the shaft 13.

Each rock-shaft 23, 24 is provided with a feed-rocker in the form of an upstanding segmental arm 34 having a projecting rib 34^a upon each of which is adjustably fitted a grooved slide-block 35 adapted to be held in adjusted position by a set screw 36 threaded through the block 35 and bearing against the side of the rib 34^a. Each slide-block 35 carries a laterally projecting stud 35^a which fits into a bore 37^a formed in the horizontal tubular end portion 37^b of a link 37, the other end portion of which is pivotally connected to the feed-frame 18. A coil spring 37^x, fitted within the bore 37^a, bears against the ends of the studs 35^a and urges the slide-blocks 35 into frictional contact with the ribs 34^a of the feed-rockers 34, when the screws 36 are released. For convenience of manufacture, and to insure simultaneous adjustment, the link connections between the studs 35^a and the feed-frame 18 are preferably combined into a single link 37, forked as at 37^b, and providing sleeves 37^c pivotally connected, at spaced points, to the cross-bar 20 of the feed-frame. Thus oscillations of the rock-shafts 23, 24 are translated into reciprocations in the feed- 75

frame 18, thereby giving to the feed-dog 16 its feed and return movements. The amplitude of the feed and return movements, and thus the length of stitch produced by the machine, is determined by the setting of the blocks 35 on the ribs 34^a nearer to or farther from the axis of oscillation of the shafts 23 and 24; the farther the blocks are adjusted from the axis of oscillation, the greater will be the movement transmitted to the feed-dog, and vice versa. Stop-screws 38 threaded into the upper ends of the ribs 34^a have their heads projecting beyond the sides of the ribs and therefore afford abutments to prevent the blocks from being slid off the upper ends of the ribs. Similar stop-screws 39 are provided at the lower ends of the ribs.

Likewise, dual means is provided for giving to the feed-frame, and the feed-dog carried thereby, their rising and falling movements in timed relation with their feed and return strokes. This means comprises a feed-lift rock-shaft 40 journaled in bearings 41 in the bed 1; a pair of feed-lift rock-arms 42 having their split hubs secured, by clamp screws 42^a, upon the shaft 40; arms 43 secured upon the guide-bars 21; and links 44 pivotally connected, at 43^a, to one end of the arms 43 and at their other ends to the rock-arms 42. Thus oscillations of the shaft 40 transmit, at two widely spaced points, rising and falling movements to the guide-bars 21 and thereby to the feed-frame 18 and the feed-dog 16.

Oscillatory movements are transmitted to the shaft 40 from an eccentric 45 on the rotary shaft 13. This eccentric is surrounded by a strap 46 carrying a sleeve 47 in which is slidably fitted a pin 48, projecting from a pinch collar 49, secured upon the shaft 40.

To enable tilting or leveling of the feed-dog 16 as may be desired, means is provided for tipping the feed-frame 18 as indicated in dotted lines in Fig. 5. This is effected by forming each of the guide-bars 21 in two pieces, viz. a cylindrical forward portion 21^a on which the feed-frame is slidably mounted and a rearward or anchor portion 21^b which is pivotally connected at 22 to the bed of the machine. The portions 21^a and 21^b are rigidly secured together by a clamp bolt 50.

When it is desired to vary the angular position of the feed-dog, the clamp bolts 50 are loosened, after which the feed-frame 18, and the feed-dog carried thereby, may be tipped about the pivotal axis 43^a between the arm 43 and link 44; the portions 21^b of the guide-rods 21 turning about their pivots 22 and the bolts 50 acting as hinge pins. After the desired adjustment has been effected, the bolts 50 are again tightened to maintain the parts in their adjusted positions.

From the foregoing, it will be perceived that 69 very strong and rigid dual drives are provided between the shaft 13 and the feed-frame 18, for giving to the feed-dog its rising-and-falling and feed-and-return strokes and that, inasmuch as those drives are transmitted to the feed-frame 65 at a plurality of spaced points, the feed-frame and the feed-dog carried thereby will be held against deflection or distortion by the stresses applied thereto.

It will also be apparent that a single means (the simultaneous adjustment of the link 37 on both segmental arms 34) has been provided for simultaneously varying the feed and return stroke transmitted to the feed-dog by the two feed-driving mechanisms.

It is to be understood that the above described

feeding mechanism may be used either separately or in conjunction with a suitable upper feeding mechanism such, for example, as that disclosed in my United States patent application Serial No. 603,656, filed July 7, 1945, as an upper and under or "clamp" feeding mechanism. Portions of said upper feeding mechanism are shown in Figs. 1 and 3 and are designated generally as *u*.

Having thus set forth the nature of the invention, what I claim herein is:

1. A work-feeding mechanism for sewing machines comprising a feed-frame, a feed-dog carried by said feed-frame, a rotary shaft, two feed-drive elements carried by said shaft, two laterally spaced and coaxially journaled feed-rockers, a driving connection between each of said feed-drive elements and a respective one of said feed-rockers, and a driving connection between each of said feed-rockers and said feed-frame for imparting work-advancing movements to said feed-dog.

2. A work-feeding mechanism for sewing machines comprising a feed-frame, a feed-dog carried by said feed-frame, a rotary shaft, two feed-drive elements carried by said shaft, two laterally spaced and coaxially journaled feed-rockers, a driving connection between each of said feed-drive elements and a respective one of said feed-rockers, a driving connection between each of said feed-rockers and said feed-frame for imparting work-advancing movements to said feed-dog, and means for simultaneously and equally adjusting the driving connections between both of said feed-rockers and said feed-frame, thereby to vary the feeding stroke transmitted to the feed-dog.

3. A work-feeding mechanism for sewing machines comprising a feed-frame, a feed-dog carried by said feed-frame, a rotary shaft, means actuated by said shaft for imparting rising and falling movements to said feed-frame and the feed-dog carried thereby, two feed-drive elements carried by said shaft, two laterally spaced and coaxially journaled feed-rockers, a driving connection between each of said feed-drive elements and a respective one of said feed-rockers, and a single link connection between both of said feed-rockers and said feed-frame for imparting work-advancing movements to said feed-dog.

4. A work-feeding mechanism for sewing machines comprising a feed-frame, a feed-dog carried by said feed-frame, a rotary shaft, two feed-drive elements carried by said shaft, two aligned rock-shafts located rearwardly of said rotary shaft, a driving connection between each of said feed-drive elements and a respective one of said rock-shafts, a rock-arm on each of said rock-shafts, and a driving connection between each of said rock-arms and said feed-frame.

5. A work-feeding mechanism for sewing machines comprising a feed-frame, a feed-dog carried by said feed-frame, a rotary shaft located below said feed-frame and extending to opposite sides thereof, a feed-drive element carried by said shaft at each side of said feed-frame, two aligned rock-shafts located rearwardly of said rotary shaft, a driving connection between each of said feed-drive elements and one of said rock-shafts, a rock-arm on each of said rock-shafts, and an adjustable driving connection between each of said rock-arms and said feed-frame.

6. A work-feeding mechanism for sewing machines comprising a U-shaped feed-frame, a feed-dog carried by said feed-frame, a rotary shaft, two feed-drive eccentrics carried by said shaft, two aligned rock-shafts located rearwardly of

said rotary shaft, a driving connection between each of said feed-drive elements and one of said rock-shafts, a rock-arm on each of said rock-shafts, and a single link connection between said rock-arms and said feed-frame.

7. A work-feeding mechanism for sewing machines comprising a U-shaped feed-frame, a feed-dog carried by said feed-frame, a rotary shaft located below said feed-frame and extending to

10 opposite sides thereof, a feed-drive eccentric carried by said shaft at each side of said feed-frame, two aligned rock-shafts located rearwardly of said rotary shaft, a driving connection between each of said feed-drive eccentrics and one of said rock-shafts, a segmental rock-arm on each of said rock-shafts, and a link pivotally connected to said feed-frame and adjustably connected to both of said rock-arms.

8. A work-feeding mechanism for sewing machines comprising a U-shaped feed-frame including spaced slide-bars and a cross-bar connecting said slide-bars, a feed-dog carried by the free end of said feed-frame, a rotary shaft located below said feed-frame and extending to opposite sides thereof, a feed-drive element carried by said shaft at each side of said feed-frame, two aligned rock-shafts located rearwardly of said rotary shaft, a driving connection between each of said feed-drive elements and one of said rock-shafts, a segmental rock-arm on each of said rock-shafts, a slide-block adjustably mounted on each of said rock-arms, a link pivotally connected at one end to the cross-bar of said feed-frame and at its opposite end to said slide blocks, and means to raise and lower said feed-frame and the feed-dog carried thereby.

9. In a sewing machine having a base and a rotary shaft journaled in said base; a pair of horizontally spaced guide-bars secured at one end to said base, a feed-frame slidably mounted on said guide-bars, a feed-dog carried by said feed-frame, two aligned rock-shafts journaled in said base rearwardly of said rotary shaft, individual means for oscillating each of said rock-shafts from said rotary shaft, a rock-arm on each of said rock-shafts, and a driving connection from each of said rock-arms to said feed-frame to reciprocate said frame on said guide-bars.

10. In a sewing machine having a base and a rotary shaft journaled in said base; a pair of spaced guide-bars secured at one end to said base, a feed-frame slidably mounted on said guide-bars, a feed-dog carried by said feed-frame, two aligned rock-shafts journaled in said base, individual means for oscillating each of said rock-shafts from said rotary shaft, and means actuated by each of said rock-shafts for reciprocating said feed-frame on said guide-bars.

11. In a sewing machine having a base and a rotary shaft journaled in said base; a pair of spaced guide-bars pivotally secured at one end to said base, a feed-frame slidably mounted on said guide-bars, a feed-dog carried by said feed-frame, two aligned rock-shafts journaled in said base, individual means for oscillating each of said rock-shafts from said rotary shaft, means actuated by each of said rock-shafts for reciprocating said feed-frame on said guide-bars, and means to adjust the position of said guide-bars thereby to vary the position of said feed-frame and feed-dog.

12. In a sewing machine having a frame including a work-support and a rotary shaft journaled below said work-support; a guide-bar comprising two adjustably connected parts of which one part is journaled on a fixed pivot carried by

said frame, a feed-frame slidingly mounted on the other part of said guide-bar, a work-advancing feed-dog carried by said feed-frame, means actuated by said shaft for reciprocating said feed-frame on said guide-bar, and means to adjust the angle between the two parts of said guide-bar, thereby to vary the position of said feed-frame and feed-dog relative to the work-support.

13. In a sewing machine having a base and a rotary shaft journaled in said base; a pair of spaced guide-bars pivotally secured at one end to said base, each of said guide-bars including an anchor section and a slide section and means securing said sections together, a feed-frame slidingly mounted on the slide sections of said guide-bars, a feed-dog carried by said feed-frame, two aligned rock-shafts journaled in said base, individual means for oscillating each of said rock-shafts from said rotary shaft, means actuated by each of said rock-shafts for reciprocating said feed-frame on said guide-bars, and means to vary the angle between the two sections of each guide-bar thereby to vary the position of said feed-frame and feed-dog relative to a horizontal plane.

14. In a sewing machine having a base, a rotary shaft journaled in said base, an oscillatory shaft journaled in said base parallel to said rotary shaft, and means for actuating said oscillatory shaft from said rotary shaft; a slidingly mounted feed-frame overlying said shafts, a feed-dog carried by said feed-frame, two aligned rock-shafts journaled in said base, individual means for oscillating each of said rock-shafts from said rotary

shaft, a rock-arm on each of said rock-shafts, a driving connection between each of said rock-arms and said feed-frame to reciprocate said feed-frame and the feed-dog carried thereby, and individual means actuated by said oscillatory shaft and connected with said feed-frame adjacent opposite sides thereof to give to said feed-frame rising and falling movements.

15. In a sewing machine having a base, a rotary shaft journaled therein, an oscillatory shaft journaled in said base parallel to said rotary shaft, a pair of rock-arms on said oscillatory shaft, and means for actuating said oscillatory shaft from said rotary shaft; a pair of parallel guide-bars each having one end pivoted to said base, a U-shaped feed-frame overlying said shafts and slidingly mounted on said guide-bars, a feed-dog carried by the free end of said feed-frame, two aligned rock-shafts journaled in said base, individual means for oscillating each of said rock-shafts from said rotary shaft, a rock-arm on each of said rock-shafts, a driving connection between each of said rock-arms and said feed-frame to reciprocate said feed-frame and the feed-dog carried thereby, links pivotally connecting said pair of rock-arms with said feed-frame to give to said feed-frame rising and falling movements, and means for adjusting said feed-frame angularly about the pivotal connection between said links and said feed-frame to vary the position of said feed-dog.

RUDOLPH BECKER.
